(57) **CLAIM**

The design for an attachment receiver for a convertible
bicycle, as shown and described.

DESCRIPTION

FIG. 1 is a top, front, and right side perspective view of an
attachment receiver for a convertible bicycle showing my
new design;

FIG. 2 is a right side elevation view thereof;

FIG. 3 is a front elevation view thereof;

FIG. 4 is a rear elevation view thereof;

FIG. 5 is a top plan view thereof;

FIG. 6 is an enlarged partial top plan view thereof;

FIG. 7 is a bottom plan view thereof;

FIG. 8 is an enlarged partial bottom plan view thereof;

FIG. 9 is an enlarged partial bottom perspective view
thereof;

FIG. 10 is an enlarged partial bottom perspective view
thereof with an exemplary footrest attachment; and,

FIG. 11 is an enlarged partial bottom perspective view
thereof with an exemplary crankset and pedal assembly
attachments.

The broken line showing of the convertible bicycle, footrest,
crankset, and pedal assembly attachments are provided for
the purpose of illustrating environmental structures and
forms no part of the claimed design.
